Primary Examiner — Austin Murphy(74) *Attorney, Agent, or Firm* — CanaanLaw, P.C.; David B. Ritchie(57) **CLAIM**

The ornamental design for an access control interface, as shown and described.

DESCRIPTION

FIG. 1 is a front right-side perspective illustration of an access control interface showing our new design;

FIG. 2 is a front elevational view thereof;

FIG. 3 is a right-side elevational view thereof, the left-side (not shown) being a mirror image thereof;

FIG. 4 is a top plan view thereof; and,

FIG. 5 is a bottom view thereof.

1 Claim, 4 Drawing Sheets(56)
